UNITED STATES PATENT OFFICE.

JOHANN FRANZ ROTH, OF BASEL, SWITZERLAND.

THREAD-WINDING APPARATUS FOR RING-SPINNING AND RING-DOUBLING MACHINES.

1,121,538.

Specification of Letters Patent. Patented Dec. 15, 1914.

Application filed April 30, 1914. Serial No. 835,400.

To all whom it may concern:

Be it known that I, JOHANN FRANZ ROTH, a citizen of the Swiss Republic, and resident of Basel, Switzerland, have invented new and useful Improvements in Thread-Winding Apparatus for Ring-Spinning and Ring-Doubling Machines, of which the following is a full, clear, and exact specification.

10 In thread winding apparatus for ring spinning and ring doubling machines in which the rings rotate with the spindle, it is known to brake the thread guides or winders which tend to rotate with the rotating 15 rings, by friction on the ring in order to make correct winding possible. While the braking devices hitherto proposed for this purpose are either not adjustable at all or only with difficulty, during the operation 20 of the apparatus, in the thread winding apparatus according to this invention, the thread guide on the rotating ring is braked according to the delivery of thread and the desired winding tension for the thread is 25 capable of being varied during the operation by means of a non-rotatable brake ring arranged adjacent to the rotating ring. This brake ring embraces the rotating ring and is adjustable relatively to the rotating 30 ring in the vertical direction. It is funnel-shaped inside and its inner conical wall will allow a braking effect during the rotation of the thread guide bearing upon it to a greater or less extent, depending on the vertical 35 position of adjustment imparted to the brake ring and in certain cases also allows a simultaneous adjustment of the friction of the guide on the rotating ring. The brake ring surrounding the rotating ring and the thread guide serves at the same time as a protector for the thread guide and the annular race therefor on the ring.

An example of construction according to the invention is illustrated in the drawing:

45 Figure 1 is the end view of the spindle beam of a ring spinning machine to which the invention is applied. Fig. 2 is a partial plan of the same. Fig. 3 is a view at a right angle to Fig. 1 the brake ring being lowered. 50 Fig. 4 shows the brake ring to an enlarged scale in conjunction with the thread guide or winder.

The thread *d* (Figs. 1-3) coming from the delivery rollers is passed onto the rotating spindle *a* shown broken away below, by

means of the winder *c* riding on the rotating ring *g* and is wound to a cop in the hollow cylindrical ring carrier *e* which is shown broken away below and rotates with the spindle *a*, by reason of the alternate 60 rising and falling of the spindle *a* in known manner.

Each rotating ring *g* is furnished with a brake ring *b* embracing it. The brake ring *b* is funnel-shaped inside and is not rotatable. The same is placed on two rods *i* and is fixed on these rods by means of the screws *k*. The rods *i* are hinged at *n* on the T-shaped support *m* and are clamped tightly against the projection *v* on the support *m* 70 when they are in the position shown in full lines in Fig. 1, in consequence of their own springiness.

The brake ring *b* can be turned downward on the support *m* into the position 75 shown in chain lines in Fig. 1, by means of a projecting finger *z*, provided on the brake ring; in this position the thread guide *c* is released from the brake ring *b* so that this latter allows of the easy introduction of the 80 thread into the guide *c*.

The support *m* is adjustable in vertical slots on a supporting rail *f* and secured thereto by screws *u*, which rail is vertically adjustable by means of a link system *g* connecting it with a control rod *r* displaceable horizontally in bearings *o*. In this way, the brake ring *b* can be vertically adjusted relatively to the ring *g* in order to cause its conical inner wall to press to a greater or less extent against the guide *c*. The rod *r* may be displaced by means of a lever *l* pivoted at *t* to the spindle beam *h*.

In the operative position of the brake ring *b*, the guide *c* swinging beyond the edge of the ring *g* bears on the smooth inner surface of the brake ring *b* upon which owing to its centrifugal force it will exert a pressure; owing to the friction thereby set up between the thread guide *c* and the inner wall of the brake ring *b*, the thread guide *c* is braked upon the ring *g*, which tends to carry it along with it, so that the thread is wound on the bare spindle or upon a cop, 100 spool or the like placed over it. By adjusting the brake ring *b*, in the vertical direction, the pressure of the guide *c* and thus its pressure on the inner surface of the brake ring can be regulated as desired during 105 the operation of the apparatus, where-

by, in certain cases, the friction of the guide on the rotating ring *g* may simultaneously be adjusted. In this way, the relation between the resultant friction between the rotating ring *g* and the guide *c* and the friction between the brake ring *b* and the guide can be varied.

In the construction shown in Fig. 3, the brake rings *b* are brought into their lowermost position by means of the lever *l*. This position allows the cops to be removed.

During the starting of the spindle *a*, the ring *g* has a tendency to carry the guide *c* resting on it, along with it. In order, therefore, to brake the guide *c* immediately the winding begins which is, of course, essential in order to prevent the thread *d* delivered by the delivery rollers from forming loops or knots, easily receding projections are arranged on the lower part of the brake ring *b*, which, when the spindle begins to rotate, are designed to effect a positive braking action on the guide. These projections consist, as best shown in Fig. 4, of freely movable balls *x* of metal, leather, cork and so forth. They are mounted in passages in the brake ring *b* inclined downward and closed at their outer end by studs *s*. At their inner end, however, they are open. This arrangement is of such a kind that the balls *x* cannot fall into the interior of the brake ring, but are always projecting sufficiently over the inner wall of the brake ring to form very resilient projections for the thread guide striking against them.

Upon starting the spindle, the brake ring *b* is lifted by means of the lever *l* to such an extent that the projecting balls *x* lie at the same level as the thread guide *c* in order to effect a positive braking action upon it (Fig. 4). Immediately the ring *g* has attained an average speed, for example, 1,000 revolutions per minute, the brake ring *b* can be brought into the desired adjusting position, for example, can be allowed to settle into the braking position shown in Fig. 1, in which the thread guide *c* is braked owing to its bearing on the inner wall of the braking ring *b*.

What I claim is:

1. In a thread winding apparatus for ring spinning and ring doubling machines, a rotary spindle, a rotary carrier arranged to rotate together with the spindle, a movable winder or thread guide upon said carrier, a non-rotatable brake ring surrounding the carrier together with the thread guide, being funnel-shaped inside and adjustable in height during the operation, and

means for adjusting said brake ring in height relatively to the guide carrier so as to cause its inner funnel-shaped wall to exert a variable braking effect upon the thread guide.

2. In a thread winding apparatus for ring spinning and ring doubling machines, a rotary spindle, a rotary carrier arranged to rotate together with the spindle, a movable winder or thread guide upon said carrier, a non-rotatable brake ring surrounding the carrier together with the thread guide and being adjustable in height during the operation, a projecting member at the inner wall of the brake ring for allowing of a positive braking of the thread guide, and means for adjusting the brake ring in height relatively to the guide carrier so as to cause a more or less strong braking of the thread guide inside the brake ring.

3. In a thread winding apparatus for ring spinning and ring doubling machines, a rotary spindle, a rotary carrier arranged to rotate together with the spindle, a movable winder or thread guide upon said carrier, a non-rotatable brake ring surrounding the carrier together with the thread guide and being adjustable in height during the operation, an easily receding projecting member at the inner wall of the brake ring for allowing of a positive braking of the thread guide, and means for adjusting the brake ring in height relatively to the guide carrier so as to cause a more or less strong braking of the thread guide inside the brake ring.

4. In a thread winding apparatus for ring spinning and ring doubling machines, a rotary spindle, a rotary carrier arranged to rotate together with the spindle, a movable winder or thread guide upon said carrier, a non-rotatable brake ring surrounding the carrier together with the thread guide and being adjustable in height during the operation, an internal projecting ball on the brake ring, freely movable in a downwardly directed passage thereof, for allowing of a positive braking of the thread guide, and means for adjusting the brake ring in height relatively to the guide carrier so as to cause a more or less strong braking of the thread guide inside the brake ring.

In witness whereof I have hereunto signed my name this 20th day of April, 1914, in the presence of two subscribing witnesses.

JOHANN FRANZ ROTH.
